UNITED STATES PATENT OFFICE.

HARVIE LEE MOORE, OF ETTRICKS, VIRGINIA.

SOUND REGULATOR.

Application filed April 26, 1928. Serial No. 273,033.

This invention relates to a sound regulator designed primarily for use in connection with portable phonographs, one of the objects being to provide a simple and compact attachment to be placed over the sound outlet of the device, the same being adjustable to partly or entirely close the outlet, thereby to correspondingly reduce the volume of sound issuing from the apparatus.

10 Another object is to provide a sound controlling device which does not mar the appearance of the apparatus, may be manufactured at low cost, and can be applied easily.

15 With the foregoing and other objects in view which will appear as the description proceeds the invention resides in the combination and arrangement of parts and in the details of construction hereinafter described and claimed it being understood that changes 20 in the precise embodiment of the invention herein disclosed may be made within the scope of what is claimed without departing from the spirit of the invention.

25 In the accompanying drawing the preferred form of the invention has been shown.

In said drawing,

Figure 1 is a top plan view of the body portion of a portable phonograph having the present improvements combined therewith.

30 Figure 2 is a section on line 2—2, Figure 1.

Figure 3 is a section on line 3—3, Figure 2.

35 Referring to the figures by characters of reference 1 designates the body portion of a portable phonograph having the usual rotatable table 2 while within one side portion of the body is formed a sound chamber 3 having an outlet 4 in the top of the body and having an inlet 5 in communication with the tone arm 6. The structure thus far described can 40 be found in many well-known makes of apparatus. The present improvement consists of a cover plate 7 which is placed on the top of the body 1 so as to bridge the outlet 4 throughout the width and length thereof, this plate 45 being held in position in any suitable manner, as by means of screws 8 extending into the body. Outlet apertures 9 are formed in the plate preferably in parallel rows and guide slots 10 are also formed in the plate between 50 the rows of apertures.

Slidably mounted on the plate 7 is a valve 11 in the form of a flat plate held to the plate 7 by headed studs 12 which are slidable with-

55 in the slots 10. Apertures 13 are formed in plate 11 and are spaced apart the same distances as the apertures 9 so that when the valve plate 11 is in one extreme position the apertures 13 will register with the apertures 9 as shown for example in Figures 2 and 3. A finger piece 14 can be formed on or connected to the valve plate whereby said plate 60 can be moved readily to any desired position. The studs 12 cooperate with the slots 10 to limit the movement of the valve plate and when said plate is in one extreme position the 65 openings 9 are fully exposed. When the valve plate is in its other extreme position the openings 9 are fully closed.

70 It will be noted that this sound controlling attachment is complete in itself and can be applied readily to a portable phonograph already constructed simply by placing the plate 7 over the outlet 4 and fastening it in position by means of the screws 8. The device is then ready for use. Obviously by regulating 75 the outlets through shifting the plate 11 the volume of sound issuing from the apparatus can be correspondingly regulated.

What is claimed is:

1. The combination with a portable phonograph having a sound chamber provided with an outlet in the top thereof, of a sound controlling attachment including an apertured plate extending over said opening throughout the width and length thereof, an apertured valve plate slidable thereon, and means for shifting the valve plate to partly or entirely close the apertures. 80

2. The combination with a portable phonograph having a sound chamber provided with an outlet in the top thereof, of a sound controlling attachment including an apertured plate extending throughout the width and length of the outlet, an apertured valve plate slidable thereon, cooperating means on the 90 two plates for holding them together and limiting the movement of the slideable plates, the apertures in the plates registering when the valve plate is in one extreme position and being closed when the valve plate is in its other 95 extreme position, and a finger piece on the valve plate. 100

3. The combination with a portable phonograph including a body having a sound chamber therein, there being an outlet from said 105 chamber opening through the top of the body,

of a sound controlling attachment including an apertured plate detachably secured to the top of the body and extending throughout the length and width of the outlet, a valve plate 5 slideable on said apertured plate and having apertures therein, cooperating means on the plates for holding them together and limit-

ing the relative movement of the slideable plate, the apertures in the plates being adapted to move into and out of register during the 10 relative movement of the plates.

In testimony that I claim the foregoing as my own, I have hereto affixed my signature.

HARVIE LEE MOORE.
